Specification for Design.

Patented Dec. 31, 1918.

Application filed April 18, 1918. Serial No. 229,448. Term of patent 14 years.

To all whom it may concern:

Be it known that I, RICHARD E. HUMBERT, a citizen of the United States, and a resident of Montclair, in the county of Essex and State of New Jersey, have invented a new, original, and ornamental Design for a Toy Head-Block, of which the following is a specification, reference being had to the accompanying drawing, forming part thereof.

I claim:

The ornamental design for a toy head block, as shown.

RICHARD E. HUMBERT.
